UNITED STATES PATENT OFFICE.

WILFORD W. DAKE, OF MUSKEGON, MICHIGAN, ASSIGNOR TO PYLE-NATIONAL ELECTRIC HEADLIGHT COMPANY, OF CHICAGO, ILLINOIS, A CORPORATION OF NEW JERSEY.

ELASTIC-FLUID TURBINE.

1,035,543.

Specification of Letters Patent. Patented Aug. 13, 1912.

Application filed December 27, 1910. Serial No. 599,286.

To all whom it may concern:

Be it known that I, WILFORD W. DAKE, a citizen of the United States, residing at Muskegon, in the county of Muskegon and State of Michigan, have invented new and useful Improvements in Elastic-Fluid Turbine-Engines, of which the following is a specification.

My invention relates to elastic fluid turbine engines, and its object is to provide an improved rotor bucket and improved methods of attaching such buckets to the rotor body of such engines. This object is attained by, and my present invention is embodied in, the mechanism hereinafter described, illustrated by the accompanying drawings, in which:

Figure 1 is a radial section of a rotor body and rotor bucket attached, illustrating my invention, and taken on line D—D of Fig. 3; Fig. 2 is a similar view, (the larger part of the rotor body broken away) taken on line Y—Y of Fig. 3; Fig. 3 is a view looking toward the rotor's axis, illustrating a method of attaching the buckets to the rotor body, several buckets being shown in section as on line C—C of Fig. 2; Fig. 4 is a view of a portion of the periphery of the rotor body looking toward its axis; Fig. 5 is a radial section of part of such rotor body, taken on line Z—Z of Fig. 4; Fig. 6 is a side view of one of the rotor buckets; Fig. 7 is a transverse section of the same on line X—X of Fig. 6; and Fig. 8 is radial sectional view of a part of the rotor body and plug, together with a bucket sectioned on the same line, and illustrating a method of attaching such bucket to the rotor body.

The rotor body 1 having the hub portion 2 carries a series of buckets 3 continuously arranged in a circle concentric with the rotor's axis. These buckets are internally concaved forward forming a curved fore wall 16, and their side walls 4 and 5 diverge from their middle point toward each face of the rotor body, as particularly shown in Figs. 1, 2 and 8, so that such diverging portions may coincide as nearly as may be with the sides of a widening or expanding jet of elastic fluid delivered or redelivered to the buckets from either side of the rotor. These buckets are preferably stamped from sheet metal and are formed with wings 6, one on each side, for attaching them to the rotor body.

In Figs. 1, 2, 3 and 4, the buckets are formed with their wings 6 inclined relatively to each other and corresponding with two annular grooves 7 in the rotor body and concentric with its axis, said grooves converging toward their bottoms, forming a dovetail 8 as shown. The wings are inserted into slots 12 formed by cutting away the overhanging portion of the dovetail 8 for a sufficient distance to admit them, such slots extending to the bottom of the grooves 7; the buckets are then moved in either direction, the wings sliding in the grooves and embracing the dovetail: when the capacity of the grooves for thus holding the buckets is reached, a screw 13 is turned into its threaded seat 14 between the slots 12 in the periphery of the rotor body as shown, such screw's head holding the last two buckets— one on either side—in place, (their wings embracing the dovetail) and, through them, the others. Or; the wings may be formed as shown in Fig. 8 and adapted to be driven into the grooves. Said figure illustrates the position of the parts at the beginning of the operation in this method of attaching the buckets to the rotor body: as the wings are driven into the grooves, they are thus forced to converge. In either method, a retaining or tightening plug, in form a continuous strip 9, serving for many or for all the buckets, may be driven in beside the wings, thus firmly binding the buckets in place on the rotor body. This done, the angular edge 10 of the rotor body between the grooves and either face of such body, may be upset or turned over inwardly to form a retaining flange 11 for securely holding the strip 9. The edges 15 of the buckets, formed by the ends of their curved fore wall, are sharp as particularly shown in Fig. 7, in order to offer as little obstruction as may be to the transversely driven jet of elastic fluid.

My invention may be embodied in varying mechanisms, and I do not propose to confine myself to the construction shown and described.

I claim:

1. In a machine of the character described, a rotor having a rotor bucket of pressed sheet metal formed with a wing portion and the interior surfaces of whose opposite walls converge a portion of their extent and then diverge, and a rotor body having an annular

groove in which such wing portion is adapted to be tightly held to fasten the bucket to the body.

2. In a machine of the character described, 5 a rotor having a rotor bucket formed with wing portions, and a rotor body having circular recesses concentric with the rotor's axis and inclined to each other in the rotor's axial plane, into which recesses the 10 wing portions respectively are inserted to fasten the bucket to the body.

3. In a machine of the character described, 15 a rotor having a rotor bucket formed with wing portions, and a rotor body having concentric annular grooves converging toward their bottoms, into which grooves the wing portions respectively are inserted to fasten the bucket to the body.

4. In a machine of the character described, 20 a rotor having a series of rotor buckets, each formed with wing portions, a rotor body having concentric annular grooves converging toward their bottoms, into which grooves the wing portions respectively of each bucket are inserted, and a continuous tightening plug driven into either groove beside the wings of a plurality of buckets to fasten the buckets to the body.

5. In a machine of the character described,

a rotor having a rotor bucket with wing 30 portions, a rotor body provided with relatively inclined concentric annular grooves holding the wing portions respectively, one of said grooves having an overhanging wall interrupted at one point by an opening to 35 admit one of said wing portions.

6. In a machine of the character described, a rotor having a recess, and a rotor bucket portion, and a rotor body having a concentric annular groove in which the wing 40 is held, a plug driven into the groove beside the wing, and a flange on the body turned over the outer extremity of the plug.

7. In a machine of the character described, 45 a rotor having a recess, and a rotor bucket formed of pressed sheet metal and having a curved forward wall and side walls whose interior surfaces converge a portion of their extent and then diverge, and having a wing portion adapted to be inserted into the recess to attach the bucket to the rotor.

In testimony whereof I have hereunto set my hand in presence of two subscribing witnesses.

WILFORD W. DAKE.
